United States Patent Office

Des. 219,981
Patented Feb. 23, 1971

219,981

INPUT DATA PREPARATION DEVICE

James F. Kleerup, Villa Park, Calif., assignor to
Peripheral Business Equipment, Inc., a corporation of
California

Filed Jan. 6, 1970, Ser. No. 20,788

Term of patent 14 years

Int. Cl. D14—02

U.S. Cl. D26—5

FIG. - 1

FIG. - 2

FIG.-3

FIG. - 4

FIG. 1 is a perspective view showing my new design;
FIG. 2 is a right side view thereof;
FIG. 3 is a rear view thereof; and
FIG. 4 is a plan view thereof.
I claim:
The ornamental design for an input data preparation
device, substantially as shown.
